UNITED STATES PATENT OFFICE.

PATRICK J. KEARNS, OF CHICAGO, ILLINOIS.

ROTARY HAMMER.

SPECIFICATION forming part of Letters Patent No. 351,867, dated November 2, 1886.

Application filed August 4, 1886. Serial No. 210,030. (No model.)

To all whom it may concern:

Be it known that I, PATRICK J. KEARNS, of Chicago, in the county of Cook and State of Illinois, have invented certain new and useful 5 Improvements in Rotary Hammers; and I do hereby declare that the following is a full, clear, and exact description of the invention, which will enable others skilled in the art to which it appertains to make and use the same, reference being had to the drawings, and to the letters of reference marked thereon, which form a part of this specification.

The object of my invention is to provide a rotary hammering-machine which has a number of hammers capable of rotating around a common center, which can be manipulated by hand or steam power, which is adapted to take the place in many instances of the hand-hammer, and which is especially useful in stone-cutting, drilling, and blacksmithing, substantially as hereinafter described, and as illustrated in the drawings, in which—

Figure 1 is a side elevation of the rotary hammers. Figs. 2 and 3 show end or edge views thereof. Fig. 4 shows a front elevation of the means employed for journaling and manipulating said rotary hammers, and Fig. 5 shows a side elevation of the machine shown in Fig. 4.

Reference being had to the drawings, A represents the standards suitably connected at the base, and having in their upper ends bearings for the shaft B. This shaft B has fast on it, between said bearings, the boss b, which has 35 four or more arms, C, projecting from it. These arms are of the same length, and have a lateral stud near their ends, on which are journaled the helves of the hammers C' C' C' C'. As the shaft revolves, these hammers swing outward as the arms to which they are pivoted move downward, and swing inward after they have struck the anvil and are being carried upward.

The anvil is placed a suitable distance from 45 the circle described by arms C, and at such a distance below the center of shaft B that the faces of the hammers strike the anvil squarely. If necessary, the helves of the hammers might be curved so as to accomplish this result.

In order to prevent the hammers from swing-

ing past the radial line of the arms C, I make integrant with or secure to the extremities of said arms the stop e, and in order to prevent the hammers swinging back upon the arms to which they are pivoted I provide stops d d. 55

In Fig. 3 is shown a series of sets of arms, C C C C, connected at their pivotal points by boss b and at their extremities by the stops e and d. The modification shown in this figure (3) is adapted for use in cutting stone. It is 60 necessary in such work to move the hammer laterally. To accomplish this the hammers may be pivoted between the extremities of any two contiguous arms C desired.

In Fig. 1 a crank is shown on the end of 65 shaft B for revolving it (and the hammers) by hand. If it is desired to operate it by steam, I extend one end of the shaft sufficiently beyond its bearings and journal loosely on its end a pulley, D. The boss of this pulley is 70 elongated laterally toward the contiguous standard, has its end edges serrated, and has a circumferential groove in it, into which the lateral pins in the bifurcated ends of the shifter-lever e enter. The opposite end of lever e 75 (which is fulcrumed between lugs projecting from the adjacent standard) is connected by the connecting-rod E to a treadle. By pressing the foot on this treadle the pulley D and elongated boss are moved laterally until the 80 serrated edges of the latter mesh with the obversely serrated edges of boss f, made fast to said shaft, and impart its motion thereto. The elongated boss of pulley D and boss f form a clutch, which imparts the motion of said pulley to the shaft B whenever desired. 85

In order to return the pulley to its original position when the foot is removed from the treadle, I surround connecting-rod E with a coil expansion-spring, F, immediately below 90 lever e, and rest the lower end thereof on a platform projecting from standard A, substantially as shown in Figs. 4 and 5. In Fig. 5 is shown another way of accomplishing the result the construction shown in Fig. 3 was designed for. In Fig. 5 the shaft between its bearings is screw-threaded and provided with a longitudinal groove. The bearing-surface of the bore of boss b is provided with a feather, which enters this groove. The boss b, &c., 95 100

revolves with shaft B, but may be adjusted laterally, which I accomplish by two set-nuts, one on either side of said boss b, as shown.

My invention may be used for driving stakes 5 or piles. To do this, however, the shaft must be capable of vertical adjustment. To accomplish this result the standards A are provided with vertical slots or openings, in which are placed and vertically adjusted the bearing-blocks G of shaft A. The blocks are tapped vertically to one side of the bearing of shaft A, for the accommodation of the vertical screws g g. The lower ends of these screws are properly journaled, and are provided with pinions h h, and are engaged by an idle-gear, H. This gear H is revolved by means of radiating hand-grasps, or any suitable way, and turns the screws g g in such way as to raise or lower the bearing-boxes G.

20 In order that the belt communication between the main shaft and pulley D may be maintained when shaft B, carrying the hammers, is adjusted vertically, an arm, I, loose on the shaft, but so connected with its boss as 25 to be shifted with pulley D, is provided. This arm has bearings in its extremity for a short shaft with pulleys on both ends, one of which is connected to pulley D and the other with the main shaft. This construction, as reference to the drawings will disclose, permits of 30 the vertical adjustment of shaft B.

As there are many ways in which the pulley and clutch connections may be shifted, I do not wish to be confined to the means herein- 35 before described.

I do not, moreover, wish to be confined to the means for operating the screws which adjust the bearing-blocks G vertically, as I have described and shown them, for it is apparent 40 that the screws might extend up through the top of the standards, and there adjust cranks to them to manipulate the screws by hand.

What I claim as new, and desire to secure by Letters Patent, is—

45 1. In a hammering-machine, the combination of the boss b, arms radiating therefrom,

having stops c, as described, and the hammers C', pivoted at or near the extremities of said arms, as set forth.

2. The combination, in a hammering-machine, with the arms C, radiating from a boss, b, of hammers C', pivoted to said arms at a suitable point between stops c and d, projecting laterally from said arms. 50

3. The combination, with arms C, radiating from a common boss, and hammers C', pivoted at or near the extremities thereof, of shaft B and means for adjusting said hammers laterally. 55

4. The combination, with arms C, radiating from a common boss, and hammers C', pivoted at or near the extremities thereof, shaft B, and bearings thereof, of screws g and means for operating the same. 60

5. The combination, with arms C, radiating from a central boss, and hammers pivoted to said arms, of shaft B, means for operating the same, and standards A, in which said shaft is journaled. 65

6. The combination, with arms C, radiating from a central boss, and hammers pivoted at or near the extremities of said arms, of shaft B, means for operating the same, standards A, bearings G, in which said shaft is journaled, screws g g, pinions h on the lower ends thereof, 75 and gear H.

7. The combination, with arms C, radiating from a central boss, hammers C', pivoted at or near the extremities of said arms, shaft B, pulley D, loose on said shaft, having elongated 80 boss, the edges of which are serrated, boss f, designed to be engaged by said pulley-boss, shifter lever e, connecting-rod E, treadle, and expansion-spring F, of standards A, bearing-blocks G, screws g g, pinion h, and gear H. 85

In testimony that I claim the foregoing as my own I hereunto affix my signature in presence of two witnesses.

PATRICK J. KEARNS.
